UNITED STATES PATENT OFFICE

2,253,272

NOZZLE HOLDER

Elwood E. Hansen, Elkhart, Ind., assignor to Elkhart Brass Mfg. Co., a corporation of Indiana

Application September 30, 1940, Serial No. 359,156

1 Claim. (Cl. 248—75)

This invention relates to improvements in nozzle holders and more especially such a device particularly adapted for holding a fire hose nozzle and supporting the same upon the running board of an automobile or other surface.

Among the features of my invention is the provision of such a device adapted to accommodate nozzles of different sizes, with very little or no adjustment.

Another feature of the invention is the provision of a nozzle support permitting easy and quick mounting or dismounting of the nozzle.

My improved nozzle support is strong and durable and yet simple in construction and operation.

Another feature of my invention is the provision of a nozzle support that can be easily attached to the running-board of an automobile or other surface, the device being so constructed that after attachment, the means of attachment are concealed.

Other features and advantages of my invention will appear more fully as I proceed with the specification.

In that form of device embodying the features of my invention shown in the accompanying drawings, Fig. 1 is a view in front elevation; Fig. 2 is a view in side elevation; Fig. 3 is a top plan view showing a nozzle supported therein; Fig. 4 is a bottom plan view; Fig. 5 is a view partly in side elevation and partly in vertical section on an enlarged scale; and Fig. 6 is a view taken as indicated by the line 6 of Fig. 1.

As shown in the drawings, the device comprises a circular base 10, with a projection 10a carrying a vertical hexagonal supporting post 11 threaded therein and held against loosening by the set screw 12.

The base 10 is provided with an annular cavity 10b on the upper surface bounded by the low outer upstanding circular flange 10c and the inner concentric somewhat higher upstanding circular flange 10d. Lying in the annular groove 10b is a rubber pad 13 which may be large enough so that it may be wedged between the flanges 10c and 10d so that it will be more securely held in place.

Mounted for vertical adjustment on the post 11 is a bifurcated clamping member 14, the jaws 14a, 14a of which are provided at their ends with upwardly and downwardly projecting fingers 14b and 14c, respectively, on which are rotatably mounted the rubber rings 15. 16 indicate brass bushings between the rings and fingers. The 55

rings are held on the fingers by the washers 17 held in place by the screws 18.

Where the jaws 14a join there is provided a rubber pad 19 with a threaded end portion 19a screwed into a suitable socket in the clamping member 14. The post 11 may be provided with a series of holes 11a, 11a adapted to receive the end of the set screw 20 to hold the clamping member 14 in its adjusted positions.

10 The upper surface of the rubber pad 13 is beveled as indicated at 13a so that nozzles of various diameters may be accommodated. In the drawings the nozzle is indicated by 21 and it will be seen that the threaded end 21a of the nozzle rests on the rubber pad 13 and is protected thereby.

15 In mounting the nozzle on the support the base is preferably first placed on the pad 13 and the body of the nozzle is then snapped between the jaws 14a of the clamping member 14. It is to be understood that the clamping member 14 has first been set to the requisite height so that the body of the nozzle can be pressed between the opposite pairs of the rubber rings 15, the latter yielding under compression sufficiently to permit the nozzle to be snapped in between the jaws or arms 14a of the clamping member 14. The nozzle will thus be held securely in place.

20 The base 10 of the support is provided with three openings 10e adapted to receive the heads of bolts (not shown) for attaching the support to a running-board of an automobile or other member. The bolts are placed in the holes 10e and the rubber pad 13 is then placed in position. 25 The pad thus covers the heads of the bolts and hides them from sight.

25 Since the rubber rings 15 are rotatable on the fingers 14b and 14c, placement of the nozzle in the support is facilitated. The clamping members 14 can be adjusted low enough so that considerable compression of the rings 15 occurs when the nozzle is placed in the support. Such placement, however, is facilitated by rotation of the rings 15. This rotation permits the nozzle being 30 pressed or snapped into place with less pressure than would be required if the rings 15 were not rotatable.

35 While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention.

tion as broadly as permissible, in view of the prior art.

What I claim as new and desire to secure by Letters Patent, is:

A device for supporting a fire hose nozzle when not in use, comprising: a base; a resilient supporting pad on the base adapted to project into the larger end of a nozzle when resting on said pad with its smaller end uppermost; a vertical post supported on the base at one side thereof; 10

and a clamping member mounted for vertical adjustment on said post, said clamping member having spaced jaws each of which carries a rotatable resilient member, whereby, a nozzle when disposed with its larger end on said pad and its smaller end uppermost, may have its body forced between said rotatable members and held in position thereby.

ELWOOD E. HANSEN.
